UNITED STATES PATENT OFFICE

2,565,637

BLENDING MACHINE

Grover C. Truslow and William M. Truslow,
Leaksville, N. C.

Application November 26, 1946, Serial No. 712,428

2 Claims. (Cl. 19—66)

1

This invention has for its object to provide an apparatus for mixing and blending various materials which are substantially in a dry state whereby an even distribution of two or more substances may be attained.

Our invention also has for its object to provide an apparatus adapted especially for use in handling various kinds of staple fibers such as wool, or cotton, mineral fibers, tobacco, feathers and like substances so that the final mixture to be employed in the manufacture of various types of goods will be an even distribution or blending of the different grades, weights, colors etc. of those products which are necessarily premixed in their original or natural states.

In a machine for the above described purpose our invention further comprehends a rotating head having a rotating discharge nozzle thereon and means for driving said elements in circular paths at appropriate relative speeds for the purpose of more efficiently distributing the substances in the so-called bedding room, also known as the gauze room.

Furthermore our invention also has for its object to provide in connection with such blending machine suitable means for the application to the fibers a spray of any desired fluid, such as oil for conditioning wool fibers preparatory to their passing to a carding machine or a spray of water for dry stocks requiring the addition of moisture before being further processed, or the application of a dye to produce a desired background color in stocks which are colored unevenly. Also there may be applied to fibers suitable chemicals such as used in the production of yarns used in the weaving of water repellent fabrics.

To these and other ends our invention comprehends further improvements in the arrangement of parts of a mixing and blending machine, all as will be fully described in the accompanying specification, the novel features thereof being set forth in the appended claims.

In the drawings:

Figure 1 is a view showing in elevation a blending machine constructed in accordance with our invention in which the material to be mixed is fed to the rotating heads from a point below them.

Figure 2 is a similar view in which the fibrous material is introduced into the heads from a point above and the spray nozzles are fed from a point below them.

Figure 3 is a diagrammatic view illustrating the manner in which the revolving heads cross and re-cross continuously during the operation of the machine.

Figure 4 is also a diagrammatic view illustrating the manner in which the discharge nozzle may be caused to rotate to effect distribution of material into the corners of a room.

Figure 5 is a detail view illustrating the adjustable mounting for the deflector.

2

In carrying out our invention we employ a supply pipe or conduit of ample cross sectional area, through which fibrous material traverses under air pressure to a laterally disposed revolving head or arm carrying a blending head or discharge nozzle in the form of a second laterally revolving arm, said arms rotating in unison to produce a gyratory effect whereby the discharge nozzle travels in a spiral path with reference to the inlet or discharge end of the supply pipe for the purpose of distributing the substances over a wide path and causing them to become thoroughly blended.

This apparatus is mounted in a bedding room which is otherwise known as the gauze room, which as shown in section in Figs. 1 and 2 comprises a floor 1, side walls, and a ceiling 2. In these figures the supply pipe 3 is shown in the former entering from one side and in the latter as entering from the top being centrally disposed in the room in each instance. In Fig. 1 the supply pipe is supported on a frame 4 and is provided with an elbow 5 at its inner end surrounded by a horizontal bearing comprising a lower stationary ring 6, supported by the frame 4, and carrying a movable ring 7. Alined with the elbow 5 is the limb 8 of a rotatable head supported on the bearing ring 7. This limb is provided with a bevel gear 9 and meshing therewith is a bevel pinion 10 on a shaft 11 the outer end of which extends exteriorly of the gauze room and may be rotated continuously from any convenient source of power, as will be understood.

The rotatable head also comprises a laterally extending arm 15 to which is strapped a framework 16 carrying a weight 17 for counterbalancing the arm and the parts carried thereon. At the outer end of arm 15 is an upwardly extending elbow 18 carrying a horizontal bearing composed of a ring 19 which is fixed to said elbow and an upper revoluble ring 20 which supports the distributing head. The latter also comprises a vertical pipe leg 21, a laterally extending arm 22 and an upwardly extending discharge end or nozzle represented by the elbow 22, the open end of which faces the ceiling 2 of the gauze room and is in proximity thereto principally for the purpose of gaining sufficient height to increase the distribution of substances as they gravitate toward the floor 1. This distribution is also aided by suspending at a short distance above the open end of the nozzle a cone shaped deflector 23, pivotally carried at the outer end of an arm 24 to which it is adjustably locked by a thumb nut 25 and as arm 24 is also adjustable vertically and secured at the points shown by lock screws 26 and 27, as shown in Fig. 5, the cone may be elevated and inclined with reference to the discharge nozzle as may be desired to best deflect the substances which impinge against it by reason of the air stream in which they are circulated.

The rotating nozzle head is counterbalanced by a weight 28 carried in a frame 29 attached to the arm of the nozzle. The latter is constantly rotated by a motor 30 the armature of which carries a bevel pinion 35 meshing with a gear ring 36 attached to the nozzle leg 21.

Counterparts of the aforescribed features are shown in Fig. 2 but since in this arrangement the supply pipe 3 enters the gauze room vertically the bearing 37 for the rotating head 38 is mounted above it and the head is carried by a frame 39 mounted on a table 40 on the upper end of a vertical shaft 41 rotatably supported on a pedestal 42. This shaft is driven by a pair of bevel gears 43 one of which is rotated by a shaft 43^a, corresponding to shaft 11 shown in Fig. 1. In this illustration we have also shown another means for rotating the blending head 44 comprising two pairs of bevel gears 45 and 46, one element of each of which is connected respectively to the inlet pipe 3 and the vertical leg of the nozzle while the other elements are fixed to a horizontal shaft 47.

In both of the arrangements shown in Figs. 1 and 2 it will be seen that by varying the relative speeds of rotation of the two heads the mixing and blending of the substances introduced through the feed pipes and emitted from the discharge nozzles may be accurately controlled. If their rotation is not at equal speeds the distributing head will follow the path depicted in Fig. 3. On the other hand, and this we consider to be an important feature of our invention, if the speed of rotation of the two heads is properly timed so that their speeds are even the distributing nozzle can be timed to swing outwardly to move its discharge end in each corner of the gauze room successively as illustrated diagrammatically in Fig. 4. There is a special advantage accomplished by this timing of the movements of the parts as it not only distributes the materials over a wider area of the gauze room floor but increases the capacity of the room by filling in its corners.

Another important feature of our invention resides in the humidifier which we employ in conjunction with the above described apparatus, said term being used in its broad sense to include the distribution of any liquid. In the handling of wool stocks certain advantages are to be obtained in their subsequent handling if these are oiled before they are processed and upon their introduction to the gauze room. Likewise where previous dyed fibers of a given base color in different shades are being blended and it is desired to render them as a given shade the best effect can be obtained by dyeing the fibers during the process of distribution and blending. Again so-called bone dry fibers may be more easily handled if they are first moistened. Another example is that of impregnating with liquid chemicals the fiber stock in the open stage which it assumes during the blending operation especially where such fibers are to be made into yarn for the weaving of waterproof fabrics since by so doing the fibers may be so successfully treated that there results but little, if any loss in the washing or scouring operations to which the textile is subjected in the finishing process.

These advantages we obtain by mounting on the underside of the rotary head a series of nozzles 50 capable of discharging an appropriate fluid in the form of a cloud mist. Such are connected to a pressure pipe 51 carried in stirrups

52 on the frames 16 and 39 as shown in Figs. 1 and 2 respectively. The pipe 51 is connected by means of a distributor gland coupling 52^a to a source of pressure supply such as the pipe 53 leading to a distant point exterior of the gauze room.

10 Electrical connections between motor 30 and a source of electrical power may be accomplished in any conventional manner desired. For the purpose of illustration we have shown in Figure 1 of the drawings a line following supply pipe 53 into the chamber. Since there is relative motion between the stationary supply pipe and the revolving head of the mechanism it is necessary to 15 employ the use of current transfer brushes which are well known in the art. These brushes are of course insulated from the supporting fluid supply pipes and comprise an upper stationary plate and a lower plate, the latter being mounted for rotation with the head. Current from the 20 lower plate brush is transferred by an electrical wire to the drive motor 30, which is in turn grounded to discharge pipe 51 as shown.

It is of course to be understood that while we 25 have illustrated certain preferred embodiments of our invention various changes in the construction and arrangement of the parts may be effected without departing from the spirit of the invention.

30 We claim:

1. In an apparatus for blending and fluid treating fibrous material the combination with a rectangular gauze room having a ceiling and floor, of a blending machine comprising a conduit for the circulation therethrough under air pressure of material to be blended, said conduit having an arm portion rotating about a vertical axis disposed centrally of the room, a framework carried by said arm, a blending head journaled on said arm and extending upwardly therefrom and having a discharge end near the ceiling, means for rotating both arm and head in timed relation to swing the discharge end successively outwardly toward and into the corners of said room, fluid pressure discharge nozzles carried by said framework and located intermediate the plane of discharge of the blended material and the room floor to act upon the material as it gravitates.

50 2. An apparatus as specified in claim 1, in which said discharge nozzles are connected to a substantially horizontal pipe carried by and rotatable with said framework, a vertically disposed extension on one end of said pipe, a pressure supply line leading to the exterior of the gauze room and having a vertical portion thereof aligned with said extension, and means connecting said vertical portion and extension permitting rotation of the pipe with the rotating arm of the blending machine.
